UNITED STATES PATENT OFFICE

103,255

DESIGN FOR A VACUUM CLEANER

Arthur A. Stone and Charles E. Cook, Highland Park, Mich., assignors to Storoco Engineering Corporation, Highland Park, Mich., a corporation of Michigan

Application July 6, 1936, Serial No. 63,687

Term of patent 3½ years

To all whom it may concern:

Be it known that we, Arthur A. Stone and Charles E. Cook, citizens of the United States, residing at Highland Park, county of Wayne, State of Michigan, have invented a new, original, and ornamental Design for a Vacuum Cleaner, of which the following is a specification, reference being had therein to the accompanying drawing,

forming a part thereof, in which there is shown a perspective view of a vacuum cleaner showing our new design.

We claim:

The ornamental design for a vacuum cleaner, substantially as shown.

ARTHUR A. STONE,
CHARLES E. COOK.
